CLAIM

The ornamental design for a multi-screen TV, as shown and described.

DESCRIPTION

FIG. 1 is a front elevational view of a multi-screen TV showing our new design;

FIG. 2 is a rear elevational plan view thereof;

FIG. 3 is a side elevational view thereof;

FIG. 4 is a top plan view thereof;

FIG. 5 is a bottom plan view thereof; and,

FIG. 6 is a rear perspective view thereof, the front view being a mirror image without the electrical plug and with the control panel as shown in FIG. 1.
